Des. 209,917
Patented Jan. 16, 1968

209,917

CARGO HOOK

Thaddeus A. Lelek, Bloomfield, N.J., assignor to Breeze Corporation, Inc., Union, N.J., a corporation of New Jersey

Filed Sept. 22, 1966, Ser. No. 3,974

Term of patent 14 years

(Cl. D54—11)

FIG. 1

FIG. 2

FIG. 3

FIG. 6

FIG. 4

FIG. 5

FIGURE 1 is a view in side elevation of a cargo hook.
FIGURE 2 is a view in rear elevation of the hook shown in FIGURE 1.

FIGURE 3 is a view in front elevation of the hook shown in FIGURE 1.

FIGURE 4 is a top plan view of the hook shown in FIGURE 1.

FIGURE 5 is a bottom plan of the hook shown in FIGURE 1.

FIGURE 6 is a view similar to FIGURE 1 with the keeper shown in the open position.

I claim:

The ornamental design for a cargo hook, substantially as shown.
